(57) **CLAIM**

The ornamental design for a smoke alarm, as shown and described.

DESCRIPTION

FIG. 1 is a front elevation view of the smoke alarm showing my new invention;

FIG. 2 is a front perspective view of the invention shown in FIG. 1;

FIG. 3 is a top perspective view of the invention shown in FIG. 1; and,

FIG. 4 is a top plan view of the invention shown in FIG. 1.
